INERTIA-OPERATED CLIMBING TOY

Robert K. Ostrander, South Orange, N. J.

Application May 24, 1947, Serial No. 750,343

7 Claims. (Cl. 46—132)

1

This invention relates to toys.

It is an object of the invention to provide a toy comprising a rod and a figure, preferably representing an animal such as a monkey, which by suitable manipulation of the rod may be caused to climb or descend the rod.

Other objects and advantages of the invention will appear hereinafter.

A preferred embodiment of the invention selected for purposes of illustration is shown in the accompanying drawings, in which,

Figure 1 is a front elevation of the toy.

Figure 2 is a side elevation.

Figure 3 is a section on the line 3—3 of Figure 1.

Referring to the drawings, the toy comprises a rod 1 of any suitable length and preferably circular in cross section. The rod may be made of any suitable material such as wood, metal or plastic, and is preferably provided with knobs 2 at its ends.

The climbing figure, here illustrated in the form of a toy monkey, comprises two relatively movable parts, an upper part 3 shaped to represent the torso, head and arms of the figure, and a lower part 4 shaped to represent the legs of the figure. The parts of the figure may be made of any suitable material such as metal, wood or plastic, and relative movement between the parts is permitted by the pivot pin 5.

Each of the parts of the figure is provided with a loop which loosely encircles the rod, the loop 6 being connected to the ends of the arms of the part 3 in the normal position of the hands, and the loop 7 being connected to the ends of the legs of the part 4 in the normal position of the feet. In the normal rest position of the figure, the position of the loop 7 is inclined to the axis of the rod so as to cause it to bind on the rod 1, thus holding the figure at any position to which it may be moved along the length of the rod.

Secured to one of the parts of the figure, and preferably to the lower part 4, is one end of a resilient member 8, the other end of which is left free so that it may vibrate freely. In the embodiment illustrated the resilient member may be shaped to resemble the tail of a monkey, and is provided at or near its free end with a small weight 9 which increases the inertia and slows the normal period of vibration of the resilient member.

In using the toy, one end of the rod 1 is grasped by the fingers and the rod is jiggled axially to cause the resilient member to vibrate. Depending upon the vigor with which the rod is jiggled

and the amplitude of vibration induced thereby, the figure is caused to climb or descend the rod by the vibration of the resilient member. This comes about in the following manner. Whenever the part 4 is caused to swing upwardly from its normal rest position by an upward movement of the resilient member, the loop 7 ceases to bind on the rod, and the climbing figure is then free to move in either direction along the rod. If the rod has been jiggled vigorously, the inertia of the resilient member on its upward stroke not only frees the loop 7, but carries the figure a short distance up the rod until the succeeding down-stroke of the resilient member again causes the loop 7 to bind on the rod. Successive up and down strokes of the resilient member will repeat the climbing motions of the figure as long as the inertia of the resilient member is sufficient to lift the figure. Whenever it is no longer sufficient, or whenever the rod is jiggled less vigorously, the upward stroke of the resilient member merely frees the loop 7, allowing the figure to slip downwardly a short distance until the succeeding down-stroke again causes the loop 7 to bind on the rod. Successive up and down strokes of this nature will repeat the descending motions.

For best results, it is advisable to limit the relative movement between the parts 3 and 4 in one direction, i. e. in the direction produced by upward motion of the resilient member. Otherwise, vigorous jiggling of the rod may cause the loop 7 to bind on the rod in the up direction, thus preventing a good climbing motion. This may be accomplished in any suitable manner as by the edge 10 on the part 4 adapted to engage the notch 11 on the part 3.

It will be understood that the invention may be variously modified and embodied within the scope of the subjoined claims.

I claim as my invention:

1. A toy comprising, a rod, a climbing figure consisting of two relatively movable parts, each of said parts including a loop loosely encircling said rod, the second of said loops having its effective diameter and axial length so correlated with the rod diameter that the loop binds on the rod when tilted axially, and a freely vibrating resilient member connected to one of said parts in position to move back and forth in directions that transmit tilting force to the second of said loops and by such coaction alternately binding and releasing the second of said loops on the rod.

2. A toy comprising, a rod, a climbing figure consisting of two relatively movable parts, each of said parts including a loop loosely encircling said

rod, the second of said loops having its effective diameter and axial length so correlated with the rod diameter that the loop binds on the rod when tilted axially, a freely vibrating resilient member connected to the same part as the second of said loops in position to move back and forth in directions that transmit tilting force to the second of said loops and by such coaction alternately binding and releasing the second of said loops on the rod, and means to limit the relative movement between said parts in one direction.

3. A toy comprising, a rod, a climbing figure consisting of two relatively movable parts, each of said parts including a loop loosely encircling said rod, a freely vibrating resilient member connected to one of said parts, and movable in directions to shift one of the loops alternately between a position in which it is tilted with respect to the axis of the rod and another position in which the loop is near enough to alignment with the rod to slide freely on said rod and a weight attached to said resilient member to increase the inertia and slow the normal period of vibration thereof.

4. A toy comprising, a rod, a climbing figure consisting of two relatively movable parts, each of said parts including a loop loosely encircling said rod, a freely vibrating resilient member connected to one of said parts and movable in directions to shift one of the loops alternately between a position in which it is tilted with respect to the axis of the rod and another position in which the loop is near enough to alignment with the rod to slide freely on said rod, a weight attached to said resilient member to increase the inertia and slow the normal period of vibration thereof, and means to limit the relative movement between said parts in one direction.

5. A toy comprising, a rod, a part constituting the torso, head and arms of a toy figure, a loop connected to said arms and loosely encircling said rod, a second part constituting the legs of said figure, a loop connected to said legs and loosely encircling said rod, said loop having its effective diameter and axial length so correlated with the rod diameter that the loop binds on the rod when tilted axially, a pivotal connection between said parts, and a freely vibrating resilient member connected to said second part and adapted, when vibrating, to cause relative movement between said parts and to move said second part alternately to positions to cause its loop to bind on and free itself from said rod.

6. A toy comprising, a rod, a part constituting the torso, head and arms of a toy figure, a loop

connected to said arms and loosely encircling said rod, a second part constituting the legs of said figure, a loop connected to said legs and loosely encircling said rod, said loop having its effective diameter and axial length so correlated with the rod diameter that the loop binds on the rod when tilted axially, a pivotal connection between said parts, a freely vibrating resilient member connected to said second part and adapted, when vibrating, to cause relative movement between said parts and to move said second part alternately to positions to cause its loop to bind on and free itself from said rod, and means to limit the relative movement between said parts in the direction which causes said last named loop to free itself from said rod.

7. A toy including, in combination, a straight rod, a climbing figure having one part constituting a torso, head and arms, and an element at the outer ends of the arms extending around the rod and connecting said upper part to the rod, said figure having a lower part constituting its legs, a pivot at one end of the second part connecting the second part to the first part, an element at the other end of the second part extending around the rod and having its width and axial length correlated with the cross section of the rod so as to bind on the rod when tilting axially with respect to the rod, a resilient member extending from the second part of the figure in a direction away from the rod and beyond the pivot, a weight attached to the resilient member for increasing its inertia and reducing its period of vibration, and means for limiting relative movement between the parts, said means including an abutment on the second part radially spaced from the pivot and in position to strike against the first part when the second part is swung about the pivot by upward movement of the weight about the pivot.

ROBERT K. OSTRANDER.
